UNITED STATES PATENT OFFICE.

ALBERT MONROE WILSON, OF CHEROKEE, IOWA.

HOSE-SUPPORTER.

1,274,225.

Specification of Letters Patent. Patented July 30, 1918.

Application filed October 17, 1917. Serial No. 197,025.

To all whom it may concern:

Be it known that I, ALBERT MONROE WILSON, a citizen of the United States, and a resident of Cherokee, in the county of Cherokee and State of Iowa, have invented a new and improved Hose-Supporter, of which the following is a full, clear, and exact description.

The invention relates to hose supporters such as shown and described in the Letters Patent of the United States, No. 755,979, granted to me March 29, 1904.

The object of the present invention is to provide a new and improved hose supporter arranged for support from the shoulders of the wearer thus relieving the nether garments, corset or the like, of all undue strain, at the same time insuring the desired ease and comfort to the wearer especially when bending the body or exercising the limbs. A further object is to prevent undue strain on the hose.

In order to accomplish the desired result, use is made of a shoulder support, a cord having its ends connected with the back of the said shoulder support, a supporting guide for the front of the cord to run in and connected with the front of the said shoulder support to form the cord into separate depending side loops, and strap guides for the hose straps running freely in the said loops.

A practical embodiment of the invention is represented in the accompanying drawings forming a part of this specification, in which similar characters of reference indicate corresponding parts in all the views.

Figure 1 is a front perspective view of the hose supporter as applied;

Fig. 2 is a perspective view of the hose supporter;

Fig. 3 is an enlarged face view of a portion of the back yoke of the shoulder straps; and

Fig. 4 is a cross section of the same on the line 4—4 of Fig. 3.

The hose supporter is supported on the shoulders of the wearer as indicated in Fig. 1, and for this purpose use is made of a shoulder support formed by shoulder straps 10 and 11 terminating at the back in a connecting member 12 to form a square back yoke. The front ends of the shoulder straps 10 and 11 are connected with each other by stitches 13 or other fastening means which are also used to attach a depending strap 14

to the front connected ends of the shoulder straps 10 and 11. A cord 15 has its ends attached to the back yoke of the shoulder straps 10 and 11, preferably at the junction of the rear ends of the straps 10 and 11 with the connecting member 12, and the front of the cord 15 runs freely in a supporting guide 16 attached to a strap 17 attached to a buckle 18 held adjustably on the lower portion of the front strap 14. By the arrangement described the cord 15 is formed into depending side loops 20 and 21 engaged by strap guides 22 and 23 running freely in the said loops and carrying straps 24 and 25 terminating in suitable fasteners 26, 27 connected with the stockings on the wearer's legs, as plainly indicated in Fig. 1. It will be noticed that by the arrangement described the cord 15 is free to slide in the supporting guide 16 and the strap guides 22, 23 are free to slide on the separate loops 20 and 21 of the cord 15, and in addition the depending front strap 14 can move readily sidewise to perfectly equalize the strain incident to the wearer bending the body or exercising the limbs, thus insuring the greatest ease and comfort to the wearer. It is understood that when the cord slides in the supporting guide 16 on the wearer bending the body then one loop 20 is increased while the other loop 21 is correspondingly decreased, thus readily compensating for the movement of the body.

The shoulder straps 10 and 11 and the connecting member 12 may be formed of one single piece of strap material and in this case the portion of the piece at the junction of the rear ends of the straps 10 and 11 with the connecting member 12 is folded and the folds are fastened together by stitches with the corresponding end of the cord 15 extending into and sewed in one of the folds, as will be readily understood by reference to Figs. 3 and 4.

Although this construction simplifies the manufacture of the hose supporter and is preferred, it is evident that I do not limit myself to the same.

Having thus described my invention, I claim as new and desire to secure by Letters Patent:

1. A hose supporter, comprising a shoulder support having a square back yoke and a V front, a cord having its ends rigidly connected with the corners of the said back yoke of the said shoulder support, a sup-

porting guide for the front of the cord to run in and connected with the apex of the said front of the said shoulder support to form the cord into separate depending side loops, and strap guides for the hose straps, running freely in the said loops.

2. A hose supporter, comprising shoulder straps connected with each other at the front and at the back, a cord having its ends spaced and rigidly fixed to the shoulder straps at the back thereof, a supporting guide for the front of the cord to run in and held on the front of the shoulder straps at the median line thereof to form the cord into separate depending side loops, and strap guides for the hose straps running freely in the said loops.

3. A hose supporter, comprising shoulder straps having a square back yoke, a V front and a front strap depending from the apex of the said V front, a supporting guide held on the said front strap, a cord rigidly attached at its ends to the corners of the said back yoke and running freely in the said supporting guide, the cord being formed into depending side loops and strap guides for the hose straps, running freely in the said loops.

4. A hose supporter, comprising shoulder straps terminating at the back in a connect-

ing strap to form a square back yoke, the said shoulder straps being connected with each other at the front, a front strap depending from the front terminal of the shoulder straps, a supporting guide attached to the lower end of the said front strap, a cord rigidly connected at its spaced ends with the said back yoke and running freely in the said supporting guide to form the cord into side loops, and hose straps provided with strap guides running freely in the loops.

5. A hose supporter, comprising shoulder straps terminating at the back in an integral connecting strap to form a square back yoke, the said shoulder straps having their front portions converging and the ends connected with each other to form a V-shaped front, a front strap depending from the apex of the said V-shaped front of the shoulder straps, a supporting guide attached to the lower end of the said front strap, a cord rigidly connected at its spaced ends with the said back yoke at the corners thereof and running freely in the said supporting guide to form the cord into side loops, and hose straps provided with strap guides running freely in the said side loops.

ALBERT MONROE WILSON.
